UNITED STATES PATENT OFFICE.

HOWARD L. INGERSOLL, OF WHITE PLAINS, NEW YORK.

LOCOMOTIVE.

Application filed April 24, 1922. Serial No. 556,228.

My invention relates to locomotives, and is especially concerned with a new type of locomotive whose driving wheels are electrically operated.

- 5 The railroad condition in the United States at the present time is practically steam operation, interrupted by a few isolated zones of electric traction in and near cities (such as the Pennsylvania Station and 60 Grand Central Terminal electrifications at New York), or in long tunnels or on exceptionally heavy grades, and varied with a few main line electrifications under very exceptional conditions (such as the Chicago, 65 Milwaukee and St. Paul). While there is a growing demand that will probably lead to many more local electrifications in urban and suburban areas, it appears very certain, nevertheless, that for a long time to come 70 sound economic considerations and the enormous first cost will prevent any general electrification.

Under present practice, local electrification entails heavy expense in the maintenance of an isolated group of special electric locomotives (with special facilities for their upkeep and repair) in each electrified area,—to say nothing of the loss of time in changing locomotives whenever a train enters or leaves such an area. Moreover, electric locomotives from one electrified area are not readily available to meet exceptional demands in another such area,—even if such areas should happen to be similarly electrified, as is often not the case. And, of course, 80 electric locomotives are absolutely useless and unavailable on unelectrified trackage. Unless, therefore, a railroad can venture to use steam locomotives in electrified areas, it must either maintain electric locomotives sufficient to meet the maximum possible demand in each and every electrified area all the time, or be liable, in some emergency, to find the capacity of its whole system 85 throttled down to that of the electric locomotives in the worst equipped area.

One principal object of my invention is to overcome this serious handicap of present conditions by provision of a novel locomotive equally adapted to operation on either electrified or unelectrified trackage. In this I aim not only to realize to the full the advantages and economies of existing electric locomotives on electrified track, but 90 also to retain unimpaired the very important advantages of the present steam loco-

motive for operation on unelectrified track,—and even to do away with some of its limitations and disadvantages without incurring new ones of any kind. Accordingly, I aim to combine the advantages of electric drive with those of operation by a power plant itself forming part of the locomotive unit, all in a thoroughly practical, 100 convenient and efficient manner.

I also aim to provide for operation of a locomotive either by current from its own power plant or generator (however the same may be driven), or by current from an outside power station transmitted directly to 70 the motors of the moving locomotive. I prefer to provide for making the change from one mode of operation to the other automatically, with little or no attention at 75 all from the engineer or locomotive driver. In a steam-operated locomotive, I prefer to employ turbo-electric generation of current in order to do away with the reciprocating and unbalanced motion which is an important drawback of the present steam locomotive, and also for convenience, economy and 80 efficiency in operation.

Various other objects and advantages attainable through the invention will appear from my description hereinafter of a steam-electric locomotive which is the best embodiment of the invention known to me.

In the drawings, Fig. 1 is a somewhat diagrammatic side elevation of a steam-electric locomotive, or locomotive unit, conveniently embodying my invention.

Fig. 2 is a corresponding plan view of the motors and drive wheels, taken about as indicated by the line 2—2 in Fig. 1.

Fig. 2^a is a plan view of the forward 95 articulated frame member or unit of the locomotive, with certain parts in section as indicated by the line 2^a in Fig. 1.

Fig. 3 is a diagrammatic representation of the turbo-electric generating apparatus, the 100 electric driving motors and their controlling means, the current collecting means for operation from trolley wire or third rail, and various accessory or auxiliary circuits and devices,—certain parts and devices appearing in section.

Fig. 4 is a somewhat diagrammatic head-on view of the locomotive, with certain steam-control devices for the turbines in section as indicated by the line 4—4 in Fig. 1, 110 on a larger scale than Figs. 1 and 2.

Fig. 5 is a generally similar but less dia-

grammatic view, with various parts pertaining to the drafting of the locomotive power plant in section as indicated by the line 5—5 in Fig. 1.

5 Fig. 6 is a diagram of the preferred system of electrical connection and control for the driving motors.

Figs. 7, 8, 9 and 10 are diagrams illustrating various operating connections and 10 conditions of the motors.

Fig. 11 is a diagram of an alarm system for indicating the condition of the motors.

The locomotive unit shown in Figs. 1, 2 and 3 comprises a locomotive proper 10 and 15 a tender 11, both resembling the corresponding ordinary steam railway equipment in general appearance and construction. The main locomotive 10 carries a steam generating plant consisting principally of an ordinary horizontal "locomotive" boiler 12, with 20 its firebox and furnace 13 and its smokebox 14; while the tender 11 carries a tank 15, etc., for the water and fuel (whether coal or oil) supplies for the steam generating plant. As 25 here shown, the locomotive 10 also carries turbo-electric generating means operable by steam from the plant 12, such means comprising a couple of steam turbines 17 (of the Curtis or other suitable type) driving 30 direct current generators 18 through interposed reduction gearing 19. All the supporting wheels 20 for both locomotive 10 and tender 11 are utilized as drive wheels, and each pair of them is accordingly provided 35 with a bipolar series wound electric motor 22, mounted directly on the axle or connected thereto in any suitable way, and operable by current from the turbo-electric means 17, 18.

40 The vehicle for the steam generating plant 12 comprises a couple of (eight wheel) units 23 articulated or connected together. As shown, each of the units 23 has a main frame with pedestal construction at one end for 45 taking the driving boxes for the axles of two pairs of drive wheels 20, and also a four-wheel truck 24 suitably mounted (with provision for lateral or other movement relative to the rest of the vehicle for taking curves) beneath 50 the other end of the unit frame with radius bar 25 suitably engaging or connected with the latter. The tender is supported by a similar (eight wheel) frame and wheel unit 23, articulated or connected to the rear locomotive unit. Similar ends of the several units 23 are coupled together,—preferably, in such a way that the trucks of tender and of front locomotive units normally lead, so as to obtain better riding and equilibrium, and 55 prevent nosing. The rear locomotive frame and wheel unit 23 extends under and supports the fire box 13 and the rear end of the boiler 12, while the forward unit 23 extends under and supports the front or smoke-box 60 end 14 of the boiler. The steam turbines 17

are supported on the forward unit 23, directly in front of the boiler 12. The electric generators 18 are also mounted on the platform 26 of this forward unit 23, beside the forward end of the boiler 12, and so, likewise, the reduction gearing 19. As shown, the turbines 17, the generators 18, the gears 19, and the smoke-box end 14 of the boiler 12 are all mounted on a rigid saddle and base structure 27 itself supported directly by the 75 platform of the unit 23.

Referring to Figs. 1, 2^a, 3, 4 and 5, it will be seen that the turbines 17 are supplied with steam by a pipe line 30, extending forward in the steam space of the boiler 12 80 from the main hand throttle 31 in the steam dome 32 to a T-head 33 in the smoke box 14. From the T-head 33, the branches 34 of the line 30 are led out through the sides of the smoke box 14, and forward to the front ends 85 of the turbines 17, which may be provided with suitable automatic speed governor mechanism, as indicated at 35 in Fig. 3. Besides the general arbitrary manual control afforded by the main throttle 31, and the individual automatic speed control afforded by governors 35, the steam supply of the turbines 17 may also be controlled individually 90 by additional starting and stopping means 36 interposed in their respective pipe lines 34 (Figs. 1, 3 and 4), and further described 95 hereinafter.

Referring, now, to Figs. 2^a and 5, it will be seen that the exhaust steam from the turbines 17 passes down into a conduit 37 in 100 the structure 27, and is conveyed rearward to operate means for producing draft for the steam generating plant 12. As here shown, the draft producing means comprises the usual petticoat pipe 38 and divided exhaust 39 in the smoke box 14. In practice, of course, the draft-producing means 38, 39 may be provided with various accessories for controlling its operation, including poppet 105 valves to prevent cinders from the smoke box 14 from passing into the turbines when either is not taking steam, etc.

When both generators 18 are in action, they may preferably operate in parallel to supply current for the driving motors 22. 115 As shown (Fig. 3), the generators 18 have a grounded inter-connection 40 (to the railway track) for one side, and may be connected in parallel to the main generator circuit 41 at the other side. The connection of 120 each generator 18 to the circuit 41 includes a self-opening switch 42, and the solenoid winding 43 for the movable core 44 that actuates such switch 42 is included in an auxiliary circuit 45 extending from said connection to a ground connection 46 (to the track). In case, therefore, the power output or voltage of either generator 18 fails or becomes too low from any cause, such 125 generator will be automatically cut off the 130

line 41 until it attains a proper value again, —i. e., generally, until its turbine 17 comes up to speed. These under-voltage circuit breakers 42, therefore, effectually prevent 5 either generator 18 from running as a motor under any condition.

The current collecting means shown comprises a pantograph trolley 47 mounted on the roof of the locomotive, and shoes 48 on 10 the trucks 24. These collecting means 47, 48 are all connected in parallel to a collector circuit 49.

The motors 22 may be operated in series, in parallel, or in series-parallel combination, —as indicated in Figs. 7 to 10. As shown in Fig. 3, one side of the power circuit 50 for these motors 22 includes a ground to the railway track as indicated at 51, while its other side extends to switch mechanism 52, 53 for connecting it to the generator circuit 41 or to the collector circuit 49, as from time to time desired. The circuit 50 extends through a controller 54, —which may be of the ordinary simple drum type, or 20 a master controller operating through shafts, or any other suitable means for controlling electric locomotives. The branch connections 50^a from the controller 54 to the several motors 22 include selective control or 30 cut-out switches 55 of any suitable type. By means of the controller 54 (itself grounded at 56 as usual) all the motors 22 collectively may be started, stopped, regulated as to speed, and generally controlled as 35 desired, in the usual manner; while by means of the switches 55, the individual motors 22 can be cut into or out of operation at pleasure. Thus the motors 22 may be operated and controlled, both collectively 40 and selectively, in any number or arrangement desired, —and this (as will presently appear) by current from either the turbo-generating means 17, 18 or the collecting means 47 or 48.

In order to make the change from operation from its own generating means to operation directly by current from an external source, it is necessary either to start or stop one or both turbines 17, or to connect or disconnect the generators 18 to or from the power circuit 50. It is preferable to do both things in making the change, and also to disconnect the collector circuit 49 from the power circuit 50 during internal 55 operation, and vice versa. I prefer to provide for making the change automatically, according to the condition of energization of the current collecting means 47 or 48, —whichever is in use. In this way, I insure 60 that whenever the collecting means ceases to be adequately energized, —whether by failure of the outside power station or of a transmission line, or by travel of the locomotive from an electrified zone of track to 65 an unelectrified one.—the locomotive will

automatically change over to operation on its own current; and that whenever the collecting means becomes adequately energized, the reverse change will occur. The change may, as here implied, be determined and 70 effected according to the adequacy of energization or voltage at the collector, even though entire deenergization thereof never occur.

As here shown, I have provided electro-magnetic means of solenoid type for performing various operations just indicated.

Referring, first, to the connection and disconnection of the power circuit 50 to and from the generators 18 and the collectors 47 80 or 48, it will be seen from Fig. 3 that the solenoid winding 61 for the movable core 62 that actuates the self-opening pivoted switch 52 is connected in an auxiliary circuit 63 itself extending from the collector circuit 49 to a ground connection 64 (to the railway track), so that when the circuit 49 is adequately energized, the switch 52 is automatically closed to connect the power circuit 50 to the collector circuit 49, 90 and vice versa. When the solenoid core 62 moves to close the switch 52, it automatically opens the spring-actuated self-closing switch 53 (here shown as an extension of 95 the switch lever 52 to the other side of its pivot), and disconnects the power circuit 50 from the generator circuit 41, —or vice versa.

Coming, now, to the starting and stopping of the turbines 17, it will be seen that the valves 70 of their automatic starting and stopping means 36 are rendered self-closing by helical compression springs 71 acting on their operating pistons 72, and are opened by fluid admitted beneath said pistons (from the main supply lines of the turbines) by self-closing relay valves 73. The solenoid windings 74 for the movable cores 75 that actuate the fluid relay valves 73 are included in branches of an auxiliary circuit 100 76 extending to ground connections 77 to the railway track, so that one or both turbines 17^a, 17^b are stopped whenever one or 105 both of the corresponding auxiliary circuit branches 76^a, 76^b are deenergized, or vice versa.

For the purpose of controlling energization of the auxiliary circuit 76 as a whole according to the adequacy of energization of the collector circuit 49 (and thus controlling the operation of the turbines 17 correspondingly), this circuit 76 is connected to a separate contact 78 on the switch arm 53 (suitably insulated from the movable contact and the rest of the switch lever 52, 53) that cooperates with the stationary generator circuit contact 79 of this switch. Inasmuch, however, as both generators 18 are idle when not in action and incapable of furnishing current to energize the circuit 76 (and, in- 115 120 125 130

4
indeed, disconnected from the generator circuit 41 by their underload circuit breakers 42) when the switch 53 closes, provision is made for an auxiliary supply of current to the circuit 76 under these conditions. As shown, such current is furnished by an auxiliary power circuit 80 extending from the contact 79 to a ground connection 81 (to the railway track) and including any suitable source of power, such as a storage battery 82. When a valve 70 has once been opened and the corresponding turbo-generator set 17, 18 has picked up so as to supply current to the circuit 76 to keep the valve open, the auxiliary power circuit 80 is automatically cut off from the contact 79 by the opening of a self-closing switch 83, whose movable core 84 is actuated by a solenoid winding 85 included in an auxiliary circuit 86 extending from the generator circuit 41 to a ground connection 87 (to the railway track),—and the battery 82 thus protected.

When the locomotive is altogether idle for any length of time (as in the round-house, or during exceptionally long stops), a normally closed hand switch 88 in the circuit 80 may be opened, concurrently with the closing of the main throttle 31, in order to prevent useless exhaustion of the storage battery 82.

By means of the switches, circuit breakers, etc., above described, therefore, the motors 22 are automatically rendered operable and controllable by energy from the current collecting means 47, 48 or from the turbo-generators 17, 18, alternatively; and the power circuit 50 is automatically energized to operate said motors from the turbo-electric means 17, 18 in the absence of adequate energization from the collecting means, and vice versa.

The combined capacity of the two turbo-generator sets 17, 18 (preferably counterparts of one another) must, of course, equal the maximum demand of the motors 22 for current under the severest starting conditions that the locomotive is expected to cope with. Since, however, the locomotive will often or generally be running under loads within the capacity of a single set 17, 18, and since the sets are most efficient under loads approximating their rated capacity,—and naturally tend (working in parallel) to divide the load equally,—it is highly desirable to shut down one set entirely whenever the load permits. To avoid grossly unequal wear and deterioration of the sets 17, 18, it is preferable that first one and then the other be put out of or into operation on the successive occasions of starting or stopping one, so that they shall likewise alternate in sole operation.

In the locomotive here illustrated, I have provided for doing all this quite automatically, by means of selective mechanism 90

interposed in the auxiliary generator control circuit 76 at the junction of the branches 76^a and 76^b with its main portion. As shown in Fig. 3, the mechanism 90 comprises a rotary insulating drum 91 fast on a shaft 92, and provided with a plurality of equally spaced peripheral contacts 93, 94 for engaging similarly spaced stationary contacts 95^a, 95^b of the branch circuits 76^a, 76^b (but incapable of bridging the contacts 95^a, 95^b, or being bridged by them). Alternate drum contacts 93 and 94 are connected, respectively, to a circuit 96 leading to an oscillatory arm 97, and to the main portion of the circuit 76. The drum 91 is turned, on occasion, by means of a pawl or dog 98 pivoted to the arm 97, and constantly spring-pressed into engagement with a toothed ratchet wheel 99 fast on the shaft 92. The arc of movement of the arm 97 and the relative adjustments of the parts are such that at each downward movement of the arm the drum 91 is turned one contact space, and brought to rest with a contact 93 or 94 in engagement with each of the branch contacts 95^a and 95^b. The arm 97 swings downward automatically, as by gravity, and is drawn upward from time to time by the influence of a solenoid winding 100 whose movable core 101 is link-connected to the free end of the arm. The solenoid winding 100 is included in a branch 102 of the generator control auxiliary circuit 76 that extends to a ground connection 103 (to the railway track). The arm 97 carries a contact 104 that engages a contact 105 of the circuit 102 whenever the arm is drawn up by the solenoid.

It will at once be apparent that the generator control circuit branch whose contact 95^a or 95^b engages one of the drum contacts 94 will be energized whenever the circuit 76 is energized, and the corresponding set 17, 18 (as shown, the set 17^a, 18^a) consequently in operation,—quite regardless of the solenoid mechanism 100, 101, etc. It will also be apparent that at each space-turn of the drum 91 by the arm 97, the two turbo-generator sets will change places in this respect. Or, in other words, operation of one set is assured whenever the contacts 78, 79 are closed; and the set to be so operated will change each time the arm 97 swings down and turns the drum 91.

The weight of the parts, etc., the strength of the solenoid 100, and the electrical resistances are preferably so proportioned that when one set 17, 18 is in operation, the solenoid will not be strong enough to draw up its core 101 until this set is operating under a load about 110% its rated capacity (which its overload features will enable it to do quite easily). When this predetermined limit is reached, the solenoid core 101 will rise and be held up with the contacts 104, 105 closed; and thus the other generator con-

trol circuit branch (as shown, 76^b) will be energized and the other set (17^b, 18^b) brought into operation to share the load. So long as the load continues sufficiently high, nothing further will happen: the core 101 and the arm 97 will remain up,—with the pawl 98 in engagement with the next higher tooth of the ratchet 99,—without acting to turn the shaft 92. Preferably, the various parts will be so proportioned that this condition will continue until the load has fallen to about 90% the rated capacity of one set 17, 18; whereupon the solenoid core 101 and the arm 97 will descend, opening the contacts 104, 105 and deenergizing the contacts 93, and also turning the drum 91 to bring a contact 94 into engagement with the contact 95 (as shown, 95^b) previously engaged with a contact 93. As a result, the set 17, 18 (as shown, the set 17^b, 18^b) last cut in will be left in service, and the other cut out. And at the next occasion of overload and its cessation, the conditions of the sets 17, 18 will be again reversed in like manner,—and so on indefinitely.

While the load on each of the sets 17, 18 is thus rather low at the critical range, the apparent disadvantage of this double under-loading is quite outweighed by the fact that it occurs only on the brief occasions of extra heavy load, and that usually the load will very quickly increase much beyond the critical range on such occasions. Such a substantial critical range as 20% between the load values for cutting a set in and out is desirable in order to obviate continual changes on very small and momentary fluctuations of load.

Referring, now, to the driving motors with their connections and control, it is to be understood that Fig. 3 affords a sketchy, generalized showing of a running condition or set of connections of the motors, with its possibilities of minor variation; Fig. 6 is a more elaborate diagram of alternative connective and control means by which the motors can be operated either in various ways; and Figs. 7, 8, 9 and 10 are diagrams representing typical operating connections of the motors that can be realized with the equipment indicated in Fig. 6.

Referring, now, to Fig. 6, it will be seen that besides the main power circuit 50 (connectible to the external circuit 41 or 49 through the switches 52, 53), the controller 54 has a plurality of motor operating circuits 111 by which the motors 22 can be variously connected between said main circuit 50 and one or more ground connections 112. Each circuit 111 has a protective fuse 113. With one exception, each of the motor operating circuits 111 is shown as adapted to include a group of two motors 22 in parallel. The exceptional motor operating circuit 111^{a-d} is a double one, adapted to include

two such parallel motor groups in series with one another. Each of the operating circuits 111 has a manual cut-out switch 114 for arbitrarily disconnecting it from the main circuit 50, so as to limit the action of the controller 54 when desired. Besides a starting rheostat loop 116 with its contactors or switches 117 for each circuit 111, the controller 54 has cut-out contactors or switches 118, 119 for disconnecting the various circuits 111 from the main circuit 50 and from the grounds 112 when motor groups are to be operated in series or in parallel series, and also shunts and contactors or switches 120, 121 and 122 for serially interconnecting the circuits 111 (with or without their rheostat loops 116). In addition, there are shunts with contactors or switches 123 and 124 for interconnecting the alternate circuits 111^a and 111^b, 111^c and 111^d, respectively. These latter shunts enable the locomotive to operate with such interconnected motor circuits in series and the intermediate circuits cut out at their switches 14th or 14th; and they also allow the circuit 111^a to be used with the rheostat loop 116^a in case its own loop 116^a is out of order, or vice versa, and similarly as to the circuits 111^b and 111^d. In the ground connection of the circuit 112^d is a shunt with an ammeter "A" for showing the current through the motors 22 in (and in series with) that circuit.

I have so far described the system shown in Fig. 6 as if the motors 22 were fixedly and permanently connected in the circuits 111. Preferably, however, provision is made for varying the connection of the motors 22^a, 22^b in the operating circuits 111^{a-d}, 111^a, 111^b, 111^c, 111^d. For this purpose each of said circuits 111 may have a pair of two-point sockets 55^a, 55^b, etc., connected therein in parallel, and each of the individual motor circuits 125 may have a two-point plug 55^a, 55^b, etc., whose insertion in one of the two-point sockets (55^a, for example) will connect the corresponding motor 22^a, 22^b, etc., (as the case may be) in series between the terminals of such socket. As shown, the circuits 125 of all these series wound bipolar motors 22 include reversing contactors 126 (four each) by means of which the connections of the armatures 127 and the fields 128 can be concurrently reversed for the purpose of reversing the locomotive. By means of these socket and plug provisions, therefore, any and every motor 22 can be connected into any and every place in the sequential operation of the controller. In a word, the number of motors 22 in service and their connections and sequential relations to one another and to the controller can be varied in every conceivable way.

Figs. 7 to 10 illustrate various desirable operating connections and groupings of

the motors 22 afforded by the control system of Fig. 6. Fig. 7 shows the most powerful starting arrangement, with six parallel motor pairs or groups in series. Fig. 8 shows a later stage, with four motor pairs in series and two (A—D) out of operation. Fig. 9 shows still a later stage, with two serially connected pairs of parallel motors in parallel. Fig. 10 shows the ordinary running condition, with four pairs in parallel. Fig. 3, of course, indicates the possibility of running with five or six pairs in parallel, if speed conditions and extra heavy loads should be found to warrant it. Obviously, of course, the Fig. 9 arrangement could be paralleled with the other two motor pairs in series; but this complication, after all, will not usually be found worth while. Generally speaking, eight motors will afford ample power and variation for all conditions of operation except starting under the heaviest loads: under that condition, operation on the booster principle with the other four motors in series may be resorted to, as indicated in Fig. 7.

It will be seen, therefore, that without any increase over a usual number of wheels for ordinary steam locomotive units, the steam-electric unit affords ample reserve of drivers and motors for starting or for cases of motor trouble. Indeed, it is possible to have four motors disabled and disconnected, and still operate the unit as an eight-motor locomotive. In such cases, all that is necessary is to "plug out" the disabled motors at 55, open the cut-out switch 114^{a-d} of the operating circuit 111^{a-d}, and "plug in" one or more of the A—D motors thus released in place of the disabled motor or motors. The disabled motors and any surplus A—D motors will then simply run idle. If more than four motors should be disabled, the sockets 55^{e-f} furthest to the left in Fig. 6 will be filled with sound ones, all the disabled ones plugged out, and an appropriate cut-out switch or switches 114 opened to suitably limit the action of the controller 54. Also, motors can be alternated with one another in the most-worked group of eight (especially under severe conditions that give rise to overheating), so as to obviate overworking or burning out of any,—and the equipment thus worn uniformly.

As an aid to this working in rotation, "temperature coils" 130 of fine copper wire may be embedded in the windings of the motors, and serially connected with indicating means such as annunciators 131, for example, in parallel across an auxiliary circuit 132 including an auxiliary source of power such as a storage battery 133. When any coil 130 is heated to a predetermined degree by overheating of a motor 22, its resistance will increase and cut down the current till the electro-magnet 134 of the corresponding

annunciator 131 can no longer hold up the disc 135,—whereupon the latter will fall and afford an indication of danger. As a means of obtaining a more definite indication of temperature when desired, an ammeter 136 70 appropriately calibrated and marked may be connected to one side of the circuit 132, and its lead 137 arranged for connection to the other side through any coil 130, by means of a three-point switch 138 by which the annunciator 131 is ordinarily connected directly thereto. When any switch 138 is shifted over, the temperature of the corresponding motor 22 will be indicated by the ammeter 80 reading at 136.

With the steam turbine rather than the internal combustion engine (such as a Diesel engine) in the locomotive power plant, not only are the disadvantages of unbalanced motion done away with, but the ability of the present steam locomotive to use either coal or oil fuel is retained. This not only avoids any necessity of changes in existing provisions for fuel supply along the railroads, but also leaves them relatively independent of oil fuel, and thus obviates the grave danger to the country of having them depend on our absolutely essential and limited supplies of military fuel. With the electric motor drive at the axles, on the other hand, uniform torque at the drivers and perfect balance are secured; all the wheels of the locomotive unit (including the tender wheels) can be made of the standard size used on present high class equipment (such as Pullman and dining cars, etc.); and all wheels of the unit are equally available for tractive purposes (whether as regular drivers, or for starting on the "booster" principle), at will, and in any combination desired. The locomotive is highly "versatile," even as compared with ordinary steam or electric locomotives: the same locomotive can be operated either on its own or on extrinsic power; it can be adapted to various local transmission systems and voltages, and to various different fuels, without any changes that involve stopping it on the road; and it can be used for either freight or passenger service, and at widely varying speeds.

Moreover, the locomotive can conform to existing standards of size and weight, so as not to entail any alterations of track, sustaining structures, clearances, or of other railroad equipment; and it can retain the present well-tried type of steam locomotive boiler plant and accessories,—which for the limited capacity (up to about 3,500 horsepower or over) is probably the most efficient steam generator in existence. Its freedom from unbalanced motion and mischievous impacts substantially increases the life of rails and track fittings, and, with the better distribution of weight which it admits of, increases the factor of safety of the track 110 115 120 125 130 135

and obviates the need for heavier and more expensive track construction with which the railroads would soon be faced under present conditions. Its own maintenance will not amount to more than about 40% that of an approximately equivalent steam locomotive.

In external operation, the steam-electric locomotive equals the ordinary electric locomotive in thermal efficiency, and surpasses it in general effectiveness, owing to the extra wheels and tractive effort available for starting, or for heavy loads and grades. In internal operation, the locomotive easily equals ordinary steam locomotives in thermal efficiency, and greatly surpasses them for starting, etc., owing both to its greater number of effective drivers and to its uniform torque at the axle. Because of the freedom from reciprocating and unbalanced parts, it can operate over much longer (twice or thrice) engine stages than are found practicable for the present steam locomotive,—which means a great deal in reducing capital charges.

In point of overall efficiency, the steam-electric locomotive in internal operation compares very favorably with railroad electrifications generally. For while (like the best present-day steam locomotives) it will consume about 2 lbs. of coal per horse-power hour, as compared with $1\frac{1}{4}$ lbs. attained in central stations supplying ordinary electric locomotives, yet the extra losses incurred in transmission, voltage variation, etc., between the central station generator and the electric locomotive draw bar come very near to making up the difference. Its ample number of drivers and its electric motor drive assure a margin of safety in maintenance of tractive power despite injury to any one motor that is absolutely unapproached and unparalleled in the present steam locomotive. The surplus of drivers for ordinary running (whether under internal or external operation) even makes it possible to do away with blowers for cooling the motors, since motors running idle cool more rapidly than they heat in service,—more rapidly, indeed, than it is possible to cool them with blowers.

I claim:

1. A steam-electric locomotive unit comprising a locomotive with a steam generating plant and turbo-electric generating means operable by steam from said plant; a tender for carrying fuel and water supply for said plant; and electric motors for driving all the carrying wheels of both locomotive and tender operable by current from said turbo-electric means.

2. A locomotive comprising electric generating means, current collecting means, electric motors for the locomotive drive wheels, and means for automatically changing over from operation of the motors by current from said generating means to op-

eration by current from said collecting means, or vice-versa.

3. A locomotive unit comprising electric generating means; current collecting means; and electric motors for the drive wheels of the unit selectively operable, in any number or agroupment desired, by current from either said electric generating means or said collecting means.

4. A steam-electric locomotive unit comprising a steam generating plant; electric generating means operable by steam therefrom; current collecting means; and bipolar electric motors for the drive wheels of the unit selectively operable, in any number or agroupment desired, by current from either said electric generating means or said collecting means.

5. A locomotive unit comprising electric generating means; current collecting means; electric motors for the drive wheels of the unit; a power circuit for said motors; and means for automatically energizing said power circuit to operate said motors from said electric generating means in the absence of adequate energization from said collecting means.

6. A locomotive unit comprising electric generating means; current collecting means; electric motors for the drive wheels of the unit; a power circuit for said motors; and means for automatically starting or stopping said electric generating means according to the condition of energization of said collecting means.

7. A locomotive unit comprising electric generating means; current collecting means; electric motors for the drive wheels of the unit; means for automatically rendering said motors operable from said electric generating means or from said collecting means, alternatively, according to the condition of energization of the latter; and means for controlling said motors both collectively and selectively.

8. A locomotive unit comprising electric generating means; current collecting means; electric motors for the drive wheels of the unit; a power circuit for said motors, with means for controlling their operation both collectively and selectively; and means for automatically connecting said power circuit either to said collecting means or to said electric generating means and disconnecting it from the other, and for stopping or starting said electric generating means, according to the condition of energization of said collecting means.

9. A locomotive comprising electric generators; electric motors for the locomotive drive wheels operable by current from said generators; and means for automatically varying the number of generators in service according to the load.

10. A steam electric locomotive unit com-

- prising a steam generating plant; turbo-electric generators taking steam directly therefrom; electric motors for the drive wheels of the unit operable by current from said generators; and means for automatically varying the number of generators in service according to the load. 5 65
11. A locomotive unit comprising electric generators; electric motors for the drive wheels of the unit operable by current from said generators; and means for cutting respective generators into and out of service in rotation as the load increases and decreases. 10 70
12. A locomotive unit comprising electric generators; current collecting means; electric motors for the drive wheels of the unit, and a power circuit for said motors; means for automatically energizing said power circuit to operate said motors from said electric generators in the absence of adequate energization from said collecting means; and means controlled by the load conditions for varying the number of generators in service. 15 75
13. A steam-electric locomotive unit comprising steam-electric generating means, including a steam generating plant and turbo-electric generators taking steam directly therefrom; current collecting means; electric motors for the drive wheels of the unit operable by current from said generating means; means controlled by the load for cutting respective generators into and out of service in alternation; and means controlled by the condition of energization of said collecting means for shutting down the turbo-electric means for operation of the motors from said collecting means. 20 80
14. A steam-electric locomotive unit comprising steam turbo-electric generating means; electric motors for the drive wheels of the unit; and means for governing the operation of said motors, including a controller for normally controlling and varying their operating connections and agroupment, and means for varying their connections and sequential relation to said controller. 25 85
15. A steam-electric locomotive unit comprising steam turbo-electric generating means; electric motors for the drive wheels of the unit; and governing means for said motors, including a controller for normally controlling operation of the motors having corresponding sockets, and means for plugging various motors into any socket, so as to put any number in any desired places in the sequential operation of the controller. 30 90
16. A locomotive unit comprising electric generating means; electric motors for the drive wheels of the unit; and governing means for said motors, including a controller for normally controlling operation of the motors having corresponding sockets, 35 95
- means for plugging various motors into any socket, so as to put any number in any desired places in the sequential operation of the controller; and means for indicating overheating of any motor. 40 100
17. A locomotive with electric motors for its drive wheels, and governing means for said motors, including a controller for normally controlling and varying their operating connections and agroupment, and means for varying their connections and sequential relation to said controller. 45 105
18. A locomotive with electric motors for its drive wheels, and governing means for said motors, including a controller for normally controlling and varying their operating connections and agroupment having sockets for the motors, and means for plugging various motors into each socket. 50 110
19. A steam-electric locomotive unit comprising steam-electric generating means, including a steam generating plant and turbo-electric generators taking steam directly therefrom; current collecting means; electric motors for the drive wheels of the unit operable by current from said generating means; means controlled by the load for cutting respective generators into and out of service in alternation; means controlled by the condition of energization of said collecting means for shutting down the turbo-electric means for operation of the motors from said collecting means; and means for governing operation of said motors from either source, including a controller for normally controlling and varying the operating connections and agroupment of the motors, and means for varying their connections and sequential relation to said controller. 55 115
20. A locomotive unit comprising electric generating means; electric motors for the drive wheels of the unit; and means for governing the operation of said motors, including a controller for normally controlling and varying their operating connections and agroupment, and means for connecting them to said controller in parallel pairs in any desired sequential relation to its operation. 60 120
21. A steam electric locomotive unit comprising vehicles each with a truck at one end inovable relatively to the rest of such vehicle for taking curves, similar ends of such vehicles being coupled together in every instance; a locomotive type steam boiler carried by two of such vehicles, and a tender carried by a third; turbo-electric generating means operable by steam from said boiler; and electric motors for all the drive wheels of the unit operable by current from said turbo-electric means. 65 125
22. A steam-electric locomotive comprising a vehicle carrying a steam-generating plant, including a horizontal boiler; electric generators on said vehicle beside the boiler

at its forward end; a truck at the front end of said vehicle, with steam turbine means for driving said generators supported by said truck in front of said boiler and taking steam therefrom; and electric motors for all the drive-wheels of the locomotive operable by current from said generators.

23. A steam electric locomotive comprising a vehicle carrying a steam-generating plant, including a horizontal boiler; electric generators on said vehicle beside the boiler at its forward end; a structure spanned between the vehicle side frames and supporting the forward end of the boiler; and steam

15 turbine means for driving said generators

mounted on said structure in front of said boiler and taking steam therefrom.

24. A steam electric locomotive comprising a vehicle carrying a steam-generating plant, including a horizontal boiler; electric 20 generators on said vehicle beside the boiler at its forward end; steam turbine means for driving said generators in front of said boiler taking steam therefrom; and means for conveying the turbine exhaust rearward 25 to draft producing exhaust nozzle means in the boiler smoke box.

In testimony whereof, I have hereunto signed my name.

HOWARD L. INGERSOLL.
